(57) **CLAIM**

The ornamental design for a residual current monitoring and protection module, as shown and described.

DESCRIPTION

FIG. 1 is a perspective view of a residual current monitoring and protection module.

FIG. 2 is another perspective view of a residual current monitoring and protection module.

FIG. 3 is another perspective view of a residual current monitoring and protection module.

FIG. 4 is another perspective view of a residual current monitoring and protection module.

FIG. 5 is front view of a residual current monitoring and protection module.

FIG. 6 is rear view of a residual current monitoring and protection module.

FIG. 7 is left side view of a residual current monitoring and protection module.

FIG. 8 is right side view of a residual current monitoring and protection module.

FIG. 9 is top view of a residual current monitoring and protection module.

FIG. 10 is bottom view of a residual current monitoring and protection module; and,

FIG. 11 is a reference view showing the use state of a residual current monitoring and protection module in accordance with a further embodiment.

The broken lines in the drawings illustrate portions of a residual current monitoring and protection module that form no part of the claimed design.

1 Claim, 11 Drawing Sheets
